UNITED STATES PATENT OFFICE.

OTTO E. GROTH, OF MILWAUKEE, WISCONSIN.

WRAPPER.

1,213,477.

Specification of Letters Patent. Patented Jan. 23, 1917.

Application filed November 21, 1914. Serial No. 373,245.

To all whom it may concern:

Be it known that I, OTTO E. GROTH, a citizen of the United States, and resident of Milwaukee, in the county of Milwaukee, 5 and State of Wisconsin, have invented new and useful Improvements in Wrappers, of which the following is a description, reference being had to the accompanying drawings, which are a part of this specification.

My invention has relation to improvements in wrappers.

The object of the invention is to provide an improved form of wrapper, more particularly adapted, although not necessarily, 15 as a wrapper for collars, cuffs and like stiff or starched articles of wear, the wrapper being of such construction that a number of collars, cuffs or like starched articles, can be wrapped in a compact circular package, 20 with but a minimum of trouble and time, and without danger of accidental unwrapping.

The invention will be particularly described in connection with its use as a wrapper for collars, as this particular adaptation 25 of the invention will serve to bring out clearly the construction and advantages of the improved device.

In the accompanying drawing, Figure 1 30 is a fragmentary view of the blank from which the improved wrapper is formed, before being folded into shape; Fig. 2 is a similar view of the wrapper folded into the form in which it is placed upon the market;

Fig. 3 is a view showing the pocket portion 35 of the wrapper, said pocket portion being partly broken away, with the ends of two collars inserted in the pocket, and also showing a fragment of the main wrapping portion of the sheet; Fig. 4 is a section on the line 4—4 of Fig. 3 looking upwardly and a portion of the pocket broken away; and Fig. 5 is a view of the wrapper as it appears when finally wrapped around a plu- 40 rality of collars.

The device is formed from a rectangular blank or sheet 6, of paper, or other suitable flexible material. This sheet toward one end thereof is cut from opposite edges inwardly, for a desired distance, on lines 7—7, 45 preferably slightly diagonal lines. From the end edge centrally is a short transversely elongated tongue 8.

In forming the complete device, the flaps 50 9 which are formed by the provision of the slits 7 are folded inwardly along the dotted

lines 10—10 and into overlapping engagement, and made to adhere to each other by an adhesive material 11 arranged longitudinally along the outer edge of one of the 60 flaps 9. The tongue 8 is then folded over the overlapping flaps 9, as clearly shown in Figs. 2 and 3, and an adhesive material 12 on the tongue 8 after being first moistened, is caused to adhere to the overlapping flaps 65 9. By this arrangement, a complete pocket 12' is formed, which has an open mouth 13 at its inner edge.

In the use of the device the ends of the collars 14, cuffs or other articles, are inserted 70 into the pocket preferably to the extent permitted by the length of the pocket, as clearly shown in Figs. 3 and 4 of the drawing. The pocket with the contained ends of the collars is then wrapped or wound into 75 circular form, and the winding is continued until the main body portion of the sheet 6 entirely surrounds not only the pocket, but the portions of the collars or other articles projecting outside of the pocket, so that a 80 circular bundle is formed, of the form clearly shown in Fig. 5. At the end of the main sheet 6 opposite to the pocket end thereof, the said sheet is provided with adhesive material 15, which adhesive material, 85 after the wrapping described is performed, is moistened so that the end of the sheet 6 can be firmly glued, to prevent accidental unwrapping of the bundle. The ends of the bundle are tucked or folded over as 90 clearly shown in Fig. 5.

The wrapping of collars or other stiff or starched articles has heretofore been difficult. Where the collars are wrapped in an ordinary sheet of wrapping paper, not only 95 is a bulky and unwieldy bundle produced, but furthermore one which is extremely liable to become unwrapped. It is, therefore, not only a source of annoyance to the clerk but also to the customer. By my improved device a most compact bundle can be formed with the least possible expenditure of time, and one in which the danger of accidental unwrapping is almost entirely avoided.

In the accompanying drawing I have illustrated a size of wrapper which is applicable particularly to a limited number of collars, two collars being shown. It is obvious, however, that by increasing the 110 width of the pocket, and the size of the main wrapping portion of the sheet, the device

may be made adaptable for a larger number of articles.

While I have described the wrapper as being preferably of paper, yet I do not wish 5 to be understood as limiting myself to that particular material, inasmuch as the wrapper may be made of any desired flexible material. It is also not absolutely necessary that the adhesive material 15 at one end of 10 the sheet be necessarily employed, inasmuch as after the wrapper is completely wound around the articles the said wrapper can be held in its wound condition by means of a string, cord or rubber band.

15 What I claim as my invention is:

A wrapper constructed entirely from a single piece of material and comprising a pocket portion and a main body portion, the

body portion being of greater length than the pocket, and said pocket portion located 20 at one edge of the body portion, the inner end of said pocket being open to provide a mouth, and said body portion extending longitudinally directly from and in line with the pocket, and having integral wings 25 projecting on each side beyond the side edges of the pocket and forming integral tucking in wings extending the entire length of the side edges of the main body portion.

In testimony whereof, I affix my signature, in presence of two witnesses.

OTTO E. GROTH.
